DEFENSIVE PUBLICATION

UNITED STATES PATENT AND TRADEMARK OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

END-OF-PATH INSERTION SYSTEM

Luther Jay Woodrum, Poughkeepsie, N.Y., assignor to International Business Machines Corporation, Armonk, N.Y.

Continuation of application Ser. No. 415,035, Nov. 12, 1973, which is a continuation of abandoned application Ser. No. 203,573, Dec. 1, 1971. This application Sept. 30, 1974, Ser. No. 510,811

Int. Cl. G06F 13/00, 13/06

U.S. Cl. 444—1

12 Sheets Drawing 41 Pages Specification

Electronically generating and inserting each entry always at the end of a path in a binary tree directory. Each new insertion entry directly displaces an existing sink found by a search of the directory with a search argument (which may be an input key). The input sequence of search arguments may be unsorted. The ascending (descending) path property is not used in a directory constructed with this invention. As a result, there is no sorted relationship among the sinks contained within this directory as occurs, on the other hand, when generating or inserting into directories constructed with the inventions using the ascending path property in prior related applications having Ser. Nos. 136,902 and 136,951 filed Apr. 23, 1971, by the same inventor as the subject application. The end-of-path insertion location is found using the search method invention in prior application Ser. No. 136,686 filed Apr. 23, 1971 by the same inventor. The inner vertices in this directory may contain edges having the absolute, offset, or invertible form.
